UNITED STATES PATENT OFFICE.

HANNIBALE ROMANO, OF SHELTON, CONNECTICUT.

COMBINATION LOCK.

Application filed October 29, 1923. Serial No. 671,366.

To all whom it may concern:

Be it known that I, HANNIBALE ROMANO, a subject of the King of Italy, residing at Shelton, county of Fairfield, State of Connecticut, have invented a new and useful Combination Lock, of which the following is a specification.

This invention relates to a combination lock, and has for an object to provide a lock 10 of this character which will be very simple in construction requiring a minimum number of parts, and one which cannot be easily picked.

It is also an object of the invention to 15 provide a lock in which a large number of different combinations may be secured, and one in which the combination is very easily changed.

With these and other objects in view, I 20 have devised the construction illustrated in the accompanying drawing forming a part of this specification, similar reference characters being employed throughout the various figures to designate corresponding elements. In this drawing,

Fig. 1 is a side elevation of the lock as applied to a door, the view being on the inner side of the door.

Fig. 2 is a view with the inner plate removed, portions of the mechanism being broken away to more clearly disclose the construction.

Fig. 3 is a longitudinal sectional plan view substantially on line 3—3 of Fig. 1.

Fig. 4 is a transverse section substantially on line 4—4 of Fig. 2.

Fig. 5 is a plan view of one of the locking discs, the view being that on the opposite side from Fig. 4.

Fig. 6 is a transverse section through this disc substantially on line 6—6 of Fig. 5, and

Fig. 7 is a detailed sectional view substantially on line 7—7 of Fig. 2.

The lock comprises a suitable metal casing 45 set into the door, preferably cast in one piece, but open on the inner side which is closed by a plate 11. At its outer end 12 it is provided with a rectangular opening 13 for the head 14 of a bolt 15, which bolt is 50 slidable in and out to lock and unlock the door. The body portion 16 of the bolt is preferably substantially cylindrical, as shown in Figs. 4 and 7, and is provided along one side thereof with a row of spaced teeth or projections 17. Extending transversely of the casing is a pair of spaced,

permanently mounted plates 18 having openings 19 therein to guide the bolt, these openings being substantially circular and approximately the size of the bolt and are 60 provided with notches 20 in one side thereof for passage of the teeth 17 when the bolt is reciprocated. Suitable means is provided for reciprocating the bolt when it is unlocked, such as a pinion 21, meshing with 65 the teeth 17, and this pinion is operated by the usual knobs 22.

For the purpose of locking the bolt a plurality of discs 23 are provided which are mounted to rotate upon the body portion 16 70 of the bolt, and the rims of these discs project through openings either in the outer wall of the casing or the plate 11, but preferably through both so that they may be operated from either side of the door. Each 75 disc is provided on one side thereof with a centrally located circular recess 24, preferably extending about half way through the disc, and mounted in this recess is a locking plate 25. The opening 26 through the disc 80 is of sufficient diameter to allow for reciprocation of the bolt in any position of the disc, but the opening 27 in the plate 25 is of substantially the same diameter as that of the body portion of the bolt and is provided on 85 one side with a notch 28 for passage of the teeth 17. It will thus be apparent that should any one of the discs be rotated so that its notch 28 is out of alignment with the teeth 17 the bolt cannot be reciprocated, 90 and in order that the bolt may be reciprocated the notches in all of the discs must be in alignment with each other and with the teeth carried by the bolt.

The plate 25 is secured in the recess of 95 the disc by means of a pair of screws 29 which pass through openings 30 in the plates and are threaded into tapped holes 31 in the disc. In the periphery of each disc are a series of notches 32 of any number desired. In the present instance I have shown 100 16 and to facilitate operation of the disc these notches are placed in outwardly projecting flanges 33. Adapted to seat in these recesses are springs 34, one for each disc, 105 and these springs are secured to an inner wall of the casing and coact with the notches to yieldingly retain the disc in different positions. The locking plates 25 may be adjusted about the axis of the disc to vary 110 the combinations. In the construction shown there are eight openings 30 in these

plates for the securing screws 29, but in order to reduce the number of tapped openings in the disc 23 for the screws, to thus reduce the work required in manufacturing 5 and also to prevent too great a weakening of the walls of the disc, it is not necessary to drill eight holes in the disc, four holes being all that is necessary. I have shown six holes but sixteen different positions may 10 be secured for the plate 18 corresponding to the sixteen different notches in the periphery of the disc by means of four holes. For this purpose a pair of diametrically positioned holes 35 are provided and 15 another pair of diametrically positioned holes 36 which are spaced from the holes 35 one half the distance between the openings 30 in the plate, or when the plate is secured with the screws in the openings 35 the openings 36 may be placed half way between any two sets of openings 30. Thus it will be apparent by having the screws in the openings 35 or 36 the plates may be positioned in any one of sixteen different positions on the disc corresponding 20 to sixteen different positions for the notches 28.

On the peripheries of the discs, spaced distances corresponding to the distances of 25 the notches 32, are provided a number of designations 37, which may be either numbers or figures or anything else desired, and to facilitate proper positioning of the discs to bring the notches 28 into alignment to unlock the bolt, a pointer 38 is provided. Suitable stops may also be provided to limit movements of the bolt, as for instance cotter pins 39.

It will be apparent that the lock is very 30 simple in construction requiring a minimum number of parts all of which are strong and durable, and therefore are not easily gotten out of order. In the present showing there are six discs and a locking plate 25 for each 35 disc each of which is adapted to cooperate with a tooth or projection 17 on the bolt to lock it either in the retracted or extended position. As the springs 34 are mounted permanently on the casing and having nothing to do with the locking or unlocking of the bolt, it will be apparent that there is no chance of their indicating to an unauthorized party when any particular disc is in 40 position to bring its notch 28 into alignment with the tooth on the bolt. It will also be apparent that a large number of different combinations may be secured either by shifting the positions of the disc on the bolt without changing the positions of the locking plate 25, by changing the positions of 45 these plates without changing the relative

position of the discs or by both. After the bolt has been shifted it may be easily locked by simply passing the thumb or finger over the discs rotating one or more of them. 65

Having thus set forth the nature of my invention, what I claim is:

1. In a lock a slidable bolt having a substantially cylindrical portion provided with a plurality of spaced teeth projecting from 70 one side thereof, a plurality of discs mounted to rotate on said bolt and each provided with a recess on one side adapted for passage of said teeth, a rotatable pinion adapted to mesh with said teeth and means for 75 rotating the pinion to slide the bolt.

2. In a lock, a slidable bolt having a plurality of spaced projections extending from one side thereof, a plurality of discs mounted to rotate on said bolt, said discs having 80 recesses on one side thereof, a plate seated in said recesses and each provided with an opening to substantially fit the bolt with a recess in one side thereof for passage of said 85 projections, means for adjustably securing the plates in the discs, and means engaging the projections for sliding the bolt.

3. In a lock, a sliding bolt having a plurality of spaced projections on one side thereof, a plurality of discs mounted to rotate on said bolt, a plate carried by each disc and having an opening through which the bolt passes, said openings having notches in one side thereof for passage of the 90 projections, said plates being provided with a plurality of equally spaced openings for securing screws, said discs being provided with two pairs of openings to receive said screws, the openings of one pair being spaced from those of the other pair a distance one half the distance between the 95 openings in the plates, and means for sliding the bolt. 100

4. In a lock, a sliding bolt having a plurality of spaced projections on one side 105 thereof, a plurality of discs mounted to rotate on said bolt, a plate carried by each disc and having an opening through which the bolt passes, said openings having notches in one side thereof for passage of the 110 projections, said plates being provided with a plurality of equally spaced openings for securing screws, said discs being provided with two pairs of openings to receive said screws, the openings of one pair being in 115 alignment with a pair of openings in the plate and the openings of the other pair being intermediate the openings in the plate and means for reciprocating the bolt.

In testimony whereof I affix my signature.

HANNIBALE ROMANO,
